UNITED STATES PATENT OFFICE.

CAREL AUGUST HOEFFTCKE, OF LONDON, ENGLAND.

SPLINT.

Application filed August 4, 1921. Serial No. 489,833.

(GRANTED UNDER THE PROVISIONS OF THE ACT OF MARCH 3, 1921, 41 STAT. L. 1313.)

To all whom it may concern:

Be it known that I, CAREL AUGUST HOEFFTCKE, a subject of the King of Great Britain, residing at London, England, have invented certain new and useful Improvements in Splints (for which I have filed an application in Great Britain Oct. 2, 1915, Patent No. 13,976), of which the following is a specification.

10 This invention refers to splints employed in what I term the ambulatory treatment of injuries or diseases of the lower limbs, applicable for instance for the treatment of fracture, shot wounds, tubercular and other 15 diseases of the joints, the office of such splints being to take the weight of the body off the leg and in addition be utilized to produce extension between the surfaces of the condyles in joint diseases, or in the case of 20 a fracture to keep the fragments in apposition.

The appliance which I have heretofore employed broadly consists of a bucket-shaped casing which embraces the upper 25 part of the thigh and buttock and upon or within which the weight of the body can be supported, while proceeding downwards from each side of the casing, on opposite sides thereof, is a rigid rod, a foot plate being fixed at the lower ends of the said rods. In some cases the rods may be jointed, having say a knee or ankle joint. To these rods the edges of a flexible support of suitable material such as canvas are adjustably fixed to 35 serve as a support for the back of the leg, while a support of similar material is also fixed to the rods to pass over the knee.

In such a splint the ankle of the patient is fitted with an ankle gaiter of flexible material, so that when the whole appliance is in position and the patient's weight is supported in the upper bucket-shaped casing, straps from the ankle gaiter pass beneath the foot plate to retain the patient's foot in 45 position, which straps can be adjusted until the requisite extension has been obtained, should such extension be desirable.

In such apparatus it is of the utmost importance that the weight of the patient 50 should be wholly sustained by the bucket-shaped thigh casing without causing injury, pain or inconvenience, and this portion of the appliance I so construct that there is no pressure at all on the perineum or pubic

bone, but the whole weight of the body is 55 transmitted to the tuberosity of the ischium and the surrounding gluteal muscles. Not only is the patient's weight thus supported without inconvenience but a great amount of extension, sometimes up to 20 or 25 pounds, 60 can be applied without discomfort, and as the result, friction between the fragments in fractures, or between the joint surfaces in joint diseases is prevented and instead of being obliged to keep the injured limb or 65 diseasen joint at rest, thereby hindering the curative process, movement can be allowed almost immediately which not only permits of exercise and prevents stagnation of the blood supply, but in fact increases it. Now 70 in treating injuries to the lower limbs particularly of wounded on the field, the employment of such apparatus as above outlined would be of incalculable benefit if it was rendered capable of immediate and 75 ready application, and was adjustable to suit any person to whom it might be desirable to apply it to and the present invention is directed to meeting these requirements.

The present invention therefore particularly refers to so constructing such a splint or appliance that it can be applied to any patient without difficulty and without lifting or raising the limb or the body of the patient, and thereby to render the appliance 80 such that it can be employed for injuries sustained to the lower limbs during war and so applied even on the field with the result of enabling the injured person to stand and even to walk a reasonable distance without 85 producing further complications or excessive pain. To this end, as hereafter described, the thigh casing or thigh bucket which is mainly constructed of rigid material preferably of metal, is divided in a vertical direction 90 into two portions, one division being at the front of the thigh bucket and the other division at the rear, so that the inner portion of the thigh bucket can be slidden underneath the buttock, this inner portion being formed so that the tuberosity of the ischium bears upon its rear inner surface. Then the outer portion can be brought 95 towards this inner and rear portion and secured by straps, flexible flaps say of leather 100 extending on the interior from the edges of the inner portion of the thigh bucket on to the inner surface of the outer portion of the

thigh bucket to cover the divisions of the said bucket. The distancing of the inner and outer portions of the thigh bucket casing is permitted by the springing apart of the downwardly extending rods.

I will further describe the invention with reference to an example of construction shown on the accompanying drawings, whereon Fig. 1 shows the appliance in front 10 elevation. Fig. 2 shows a side elevation of the appliance shown in Fig. 1, the appliance actually shown in these two views being adapted to be applied to the right leg, and Fig. 2 showing the external side of the appliance.

Fig. 3 shows the bucket-shaped thigh casing illustrating the rear division. Fig. 4 is a similar view to Fig. 3 showing principally the inner portion of the thigh casing. 20 The bucket-shaped casing consists of the two parts or portions previously mentioned, the part indicated at 1 being the rear inner portion formed at about 2 so that it supports the tuberosity of the ischium, and 3 is the outer portion of the thigh casing. The rearward division 4 and the frontal division 5 of the thigh casing are clearly shown in the drawings, and adjustable straps or equivalent connections such as 6 are fitted between

30 the two parts 1 and 3 so that they can be wholly separated, and when connected together by the straps 6 the edges of the divisions 4 and 5 can be varied as regards the distance from one another, and thereby the 35 thigh casing adapted to the size of the individual patient to whom it is to be applied. Leather flaps such as 7 are fitted to one part or the other, in the casing illustrated to the part 1 upon the interior surface and 40 overlying the edges of the part 3 of the thigh casing so as to cover the division.

Adjustably fixed respectively to the part 1 and to the part 3 of the thigh casing are downwardly extending rods 8, at the lower 45 ends of which a rigid or jointed foot plate 9 of metal is fixed. As a detail of construction, both the rods 8 may be formed from a single strip and be bent beneath the foot plate so that the latter is secured or jointed 50 thereto.

Such a structure is very light in weight when manufactured, and it will be observed that if the straps 6 are disconnected, the parts 1 and 3 of the thigh bucket can be 55 distanced from each other quite easily owing to the elasticity of the rods 8, so that without

moving the limb of the patient, the rear portion 1 can be passed between the thighs and placed around and onto the buttock of the 60 injured limb, and the outer portion brought thereonto while the leg of the patient is between the rods 8, and then it is only necessary to adjust and fasten the straps 6, which can quite well be done, con- 65 sidering the position of the divisions of

the thigh casing, without moving the patient, and by this adjustment the parts 1 and 3 of the thigh casing can be so brought together as to fit the patient and permit his weight and the strain of extension where

such is applied to be supported without the said patient suffering much pain and inconvenience.

Between the rods 8 I fix the flexible supporting member 10 for the back of the patient's leg, and such support, in order to adapt it to various lengths of limbs is adjustably fixed to the said rods by, for instance, straps 11 passing over studs 12. A similiar flexible frontal supporting member

13 is applied by a similar fixing to pass over the patient's knee. In some cases the flexible supports can be dispensed with and bandages employed instead. As aforesaid, the rods 8 can be adjustable in length so as to distance the foot plate 9 from the thigh casing as required, in such manner that the heel of the patient does not rest on the foot plate, and around the patient's ankle I fix an ankle gaiter such as 14, from which a strap 15 and buckle 16 extends, passing beneath the sole of the footplate by which the extension can be obtained.

What I claim and desire to secure by Letters Patent is:—

1. An ambulatory splint employed in the treatment of injuries or diseases of the lower limbs; comprising a thigh casing of substantially rigid material divided in a vertical direction into two separable and relatively adjustable portions to permit said thigh casing to be applied without disturbing the patient, means for connecting one portion of said thigh casing to the other portion and for adjusting the distance apart of the edges of said portions of said thigh casing, two rods extending about parallel with the leg of the patient one upon each side thereof, means for fixing the upper ends of said rods one to one portion and one to the other portion of said divided thigh casing, a foot plate, means for rigidly connecting said foot plate to the lower ends of said rods at a greater distance from said thigh casing than the length of the patient's leg, 115 an ankle gaiter to embrace the ankle of the patient located between said rods and adjacent said foot plate, and flexible connections from said ankle gaiter to pass beneath the sole of said foot plate to bring about 120 extension of the patient's leg.

2. An ambulatory splint employed in the treatment of injuries or diseases of the lower limbs; comprising a thigh casing of substantially rigid material divided in a vertical direction into two separable and relatively adjustable portions to permit said portion 1 can be passed between the thighs and placed around and onto the buttock of the patient, and the outer portion brought thereonto while the leg of the patient is between the rods 8, and then it is only necessary to adjust and fasten the straps 6, which can quite well be done, con- 65 sidering the position of the divisions of said thigh casing being of larger periphery 130

- and of greater depth than the front outer portion thereof, means for connecting one portion of said thigh casing to the other portion and for adjusting the distance apart of the edges of said portions of said thigh casing, two rods extending about parallel with the leg of the patient one upon each side thereof, means for fixing the upper ends 70 of said rods one to one portion and one to the other portion of said divided thigh casing, a foot plate, means for rigidly connecting said foot plate to the lower ends of said rods at a greater distance from said thigh 75 casing than the length of the patient's leg, an ankle gaiter to embrace the ankle of the patient located between said rods and adjacent said foot plate, and flexible connections from said ankle gaiter to pass beneath 80 the sole of said foot plate to bring about extension of the patient's leg.
5. An ambulatory splint employed in the treatment of injuries or diseases of the lower limbs; comprising a thigh casing of substantially rigid material divided in a vertical direction into two separable and relatively adjustable portions to permit said thigh casing to be applied without disturbing the patient, the rear inner portion of 85 said thigh casing being of larger periphery and of greater depth than the front outer portion thereof, the said front outer portion having inclined upper and lower edges approximately parallel to one another: means for connecting one portion of said thigh casing to the other portion and for adjusting the distance apart of the edges of said portions of said thigh casing, two rods extending about parallel with the leg of the patient one upon each side thereof, means for 90 fixing the upper ends of said rods one to one portion and one to the other portion of said divided thigh casing to permit the adjustment of said rods in a downward or upward direction, a foot plate, means for rigidly connecting said foot plate to the lower ends of said rods at a greater distance from 95 said thigh casing than the length of the patient's leg, a rear flexible supporting member for the back of the patient's leg, means for adjustably connecting the edges of said rear supporting member to said oppositely located rods, a frontal flexible supporting member to pass over the knees of the patient, means for adjustably connecting 100 said frontal supporting member to said rods, an ankle gaiter to embrace the ankle of the patient located between said rods and adjacent said foot plate, and flexible connections from said ankle gaiter to pass beneath 105 the sole of said foot plate to bring about extension of the patient's leg.
4. An ambulatory splint employed in the treatment of injuries or diseases of the lower limbs; comprising a thigh casing of substantially rigid material divided in a vertical direction into two separable and relatively adjustable parts to permit said thigh casing to be applied without disturbing the patient, the rear inner portion of 110 which is of a shape to receive the tuberosity of the ischium and the surrounding gluteal muscles but leaving the perineum and pubic bones free of pressure, means for connecting one portion of said thigh casing to the other 115
6. An ambulatory splint employed in the treatment of injuries or diseases of the lower limbs; comprising a thigh casing of substantially rigid material divided in a vertical direction into two separable and relatively adjustable portions to permit said thigh casing to be applied without disturbing the patient, interior leather flaps to 120 bridge over the spaces between the edges of said divided casing, straps on one part of said divided casing and buckles on the other part for connecting one portion of said thigh casing to the other portion and for adjusting 125

the distance apart of the edges of said portions of said thigh casing, two rods extending about parallel with the leg of the patient one upon each side thereof, means 5 for fixing the upper ends of said rods one to one portion and one to the other portion of said divided thigh casing to permit adjustment of said rods in a downward or upward direction, a foot plate, means for 10 rigidly connecting said foot plate to the lower ends of said rods at a greater distance from said thigh casing than the length of the patient's leg, a rear flexible supporting member for the back of the patient's 15 leg, means for adjustably connecting the edges of said rear supporting member to

said oppositely located rods, a frontal flexible supporting member to pass over the knee of the patient, means for adjustably connecting said frontal supporting member 20 to said rods, an ankle gaiter to embrace the ankle of the patient located between said rods and adjacent said foot plate, and flexible connections from said ankle gaiter to pass beneath the sole of said foot plate to 25 bring about extension of patient's leg.

In witness whereof I have hereunto set my hand in the presence of two witnesses.

CAREL AUGUST HOEFFTCKE.
